UNITED STATES PATENT OFFICE.

AUGUST BÜTTNER, OF UERDINGEN, GERMANY.

CELLULAR DRYING APPARATUS.

1,078,125.

Specification of Letters Patent.

Patented Nov. 11, 1913.

Application filed May 9, 1912. Serial No. 696,230.

To all whom it may concern:

Be it known that I, AUGUST BÜTTNER, a subject of the King of Prussia, residing at Uerdingen, Kingdom of Prussia, German Empire, have invented certain new and useful Improvements in Cellular Drying Apparatus, of which the following is a specification.

In drying cylinders in which the material to be dried is moved in the same direction as the air current, the movement of the material is principally effected by the air current and only partially by the inclined position of the cylinder. The lighter the material the greater is the action of the air current so that the speed of the material gradually increases toward the outlet of the cylinder as the material gets gradually lighter during its passage through the cylinder in consequence of its being drained. This reduction of weight being very considerable for certain materials, the weight of the material at the outlet is often only $\frac{1}{2}$ of the weight at the inlet, the air current acts at the outlet end of the cylinder much stronger upon the material than at the inlet end whereby the inconvenience is caused that the material to be dried passes too quickly through the second half of the cylinder. The efficiency of the machine is thus unfavorably influenced. This inconvenience is overcome according to this invention by providing in the cylinder resistances which gradually increase in number and in capacity toward the end of the cylinder.

In the accompanying drawings the drying machine is shown by way of example.

Figure 1 represents a cellular drying cylinder which is divided into three compartments. Figs. 2, 3 and 4 are cross sections of Fig. 1 on lines A—A, B—B and C—C respectively. Fig. 5 shows in front elevation the upper half of the compartment 1 of a cylinder with square cells. Figs. 6 and 7 show the same cells as Fig. 5 for the compartments 2 and 3. Fig. 8 shows in front elevation the upper half of the compartment 1 of the cylinder with segment shaped cells. Figs. 9 and 10 show the same cells as Fig. 8 for the compartments 2 and 3. Figs. 11, 12, 13 and 14 show in front elevation the upper half of the cylinder with cells of modified construction. Fig. 15 is a developed plan view of part of Fig. 9. Fig. 16 shows in

plan view one of the cells of Fig. 11. Fig. 17 is a developed plan view of Fig. 18. Fig. 18 shows in plan view a cell of modified construction.

According to the invention the cylinder of the drying machine is divided into three compartments 1, 2, 3 which freely communicate the one with the other. The first compartment 1 is divided into a certain number of cells 6 by means of partitions which according to Fig. 2 form hexagonal cells. In compartment 2 the cells 6 have three cross partitions 7. In compartment 3 six partitions 7 are provided.

According to Fig. 5 the cells 6 can be of square cross section. The cells 6 for the compartment 2 are subdivided by a horizontal partition 7 and for the compartment 3 they are subdivided by a horizontal and by a vertical partition 7.

According to Figs. 8, 9 and 10 the cells 75 are segment shaped with one additional radial partition for the compartment 2 and with a radial and a concentrical partition for the compartment 3.

The cells according to Figs. 11, 12, 13 and 14 are arranged so that either the vertical walls (Fig. 11) or the horizontal walls (Fig. 12) are interrupted alternatingly at the one or at the other end.

According to Figs. 13 and 14 the ends of the horizontal or vertical partitions respectively of the cells are bent at right angles. The length of the compartments 1, 2, 3 depends on the kind of material to be dried.

The device operates as follows:—The material to be dried which is fed to the drying cylinder 1 at the end 11 of the same is moved in the well known manner through the drying cylinder by the air current which enters the drying cylinder at the same end 11 as the material. The speed of the material is greatest in the first compartment near the cylinder inlet and it is impeded in compartment 1 by the additional partitions of the cells. The speed is further reduced in the third or end compartment by further additional partitions and the material dried gets out at the open end 5 of the drying cylinder.

I claim:

A cellular drying cylinder in which the 105 current of heated air moves in the same direction as the material to be dried, comprising in combination with the cylinder, con-

tinuous cells of any convenient cross section, a certain number of additional partitions in the cells of the middle part of the cylinder and further additional partitions in the cells of the end part of the cylinder, substantially as described and shown and for the purpose set forth.

In witness whereof I have hereunto set my hand in the presence of two witnesses.

AUGUST BÜTTNER.
